Philip Langford, Jr.

UNITED STATES PATENT OFFICE.

CHARLES W. VALENTINE, OF WATERTOWN, NEW YORK, ASSIGNOR TO THE BAGLEY AND SEWALL COMPANY, OF WATERTOWN, NEW YORK, A CORPORATION OF NEW YORK.

PAPER-MAKING MACHINE.

Application filed January 12, 1927. Serial No. 160,722.

This invention relates to certain improvements in steam heated rotary cylinders such as the dryer rolls for paper making machines, and particularly to improvements in 5 the steam joints and the mechanism for supporting and adjusting the siphon tube used with such dryers.

While the invention as to certain of its 10 features has been designed for and is useful with various revolving hollow rolls or cylinders to which steam is supplied, or from which water needs to be extracted, the invention will be described as employed with the drying rolls or cylinders of paper making 15 machines, for which it has been particularly designed.

Dryers for paper making machines comprise large hollow cylinders over which the web passes from the making end of the machine. These cylinders are usually heated by steam and, where steam is used, means must be provided for supplying the steam and withdrawing the water of condensation 20 from the cylinders. This is usually effected by some form of steam joint and a siphon tube or pipe which extends into the dryer. To be effective, it is necessary that the suction end of this siphon be near the bottom of the cylinder, but, in order to avoid injury 25 to the pipe, it is desirable that the suction end of the pipe shall not contact with or drag on the wall of the cylinder, for if the pipe is permitted to so drag it will wear so as to conform with the cylinder wall 30 forming a seal, which thus destroys its function.

It is the special object of the present invention to provide an improved steam joint and an improved construction for supporting 40 the steam joint and determining the position of the suction end of the siphon pipe, so that the operator can tell by the feel of the pipe when it is in contact with the cylinder wall and can then adjust the pipe so 45 that it will lie in the desired position close to but out of contact with the wall of the cylinder.

A further object of the invention is to 50 provide such a construction in which this adjustment of the pipe can be effected while the machine is either running or standing still.

A further object of the invention is to provide an improved support for the pipe and an improved steam joint or steam connection which will relieve the pipe of load and end thrust, and which at the same time will be steam-tight. 55

With these and other objects not specifically referred to in view, the invention consists in certain novel parts, arrangements and combinations which will be described in connection with the accompanying drawings and the novel features pointed out in the claims hereunto annexed. 60

In these drawings,—

Figure 1 is a central side elevation, partly broken away, of the improved construction for supporting and adjusting the siphon pipe and supporting the steam joint; 70

Figure 2 is a sectional broken away view showing the relation of the siphon and the drying cylinder with which it is used;

Figure 3 is a detail sectional view taken on the line 3—3 of Fig. 1; 75

Figure 4 is a further detail sectional view taken on the line 4—4 of Fig. 1, and

Figure 5 is an enlarged sectional view of the adjusting mechanism shown in Fig. 1.

Referring now to these drawings, the improved siphon arrangement has been shown as employed with a drying cylinder 1, it being understood that the construction will be used with all or as many of the drying cylinders of the machine as may be desired. 80 As the construction is the same, but one drying cylinder has been illustrated. This drying cylinder is steam-tight, being formed with heads 2, one of which is shown, which head is formed with a journal 3 by which the drying cylinder is rotatably supported in any suitable framing, not shown. Secured to the end of the journal and revolving with it is a packing box and a bearing of improved construction, which receive certain 95 parts hereinafter referred to. This improved packing box and bearing are arranged so as to be steam-tight, and form a steam joint. While the particular construction of these may be somewhat varied, it 100 will, as shown, comprise two parts—a packing gland and a bearing independent of the gland. As shown, this packing box and bearing are secured to the end of the journal

in any suitable manner, as by means of bolts 4. The packing gland includes a flange ring 5 to which is secured, by bolts 6, a collar 7, packing 8 being provided between the collar and the ring. Beyond the ring, but secured thereto by a web 9, is a roller bearing comprising a casing 10 and rollers 11.

It will be seen with this construction that the bearing is entirely outside and independent of the packing gland, so that there is no access thereto of steam or water, which is a desirable feature. Furthermore, this bearing takes all the load due to the weight of the parts or steam pressure, so that the only function of the packing gland is that of a seal.

It will be understood that the parts so far described rotate with the journal of the drying cylinder. Mounted so as to extend a suitable distance into the hollow journal 3 is a sleeve 12. This hollow sleeve passes through the packing gland, and the roller bearing revolves on this sleeve, which is secured by means of bolts 13 to a connection 14 which has a steam chamber 15 connected with the steam inlet 16 and a water chamber 17 connected with the water outlet pipe 18. These chambers 15, 17 are divided by a web 19, hereinafter referred to.

30 The water of condensation is removed from the drying cylinder by means of a siphon pipe 20 which is supported at one end in a spider 21 in the inner end of the sleeve 12 and at its other end in a bearing 22 secured to the connection 14, before referred to, packing 23 being provided in the bearing to seal the parts. This siphon tube, it will be observed, extends through the hollow journal 3 into the drying cylinder and is 40 curved downwardly so as to lie close to the inner surface of the cylinder.

In accordance with the invention, means are provided whereby the position of the suction-end 24 of this siphon pipe 20 may 45 be accurately adjusted by the operator, and this mechanism will be such that the operator can make the necessary adjustments without having to look or get into the drying cylinder. These means may be somewhat varied. There will be provided, in the best 50 constructions, means by which the pipe as a whole may be swung around the dryer so that any dragging of the end of the pipe with the inner surface of the dryer shell may 55 be readily felt by hand and the siphon then adjusted to bring the suction end the desired distance from the inner surface of the cylinder wall.

As shown, the siphon pipe is formed at its 60 outer end with a closed head provided with a projection 25 to which is secured, by a set screw 26, a handle 27. This handle may be locked in position by means of a stop pin 28, which works in a projection 29 formed on the handle and enters a recess, in-

dicated at 30, in the end wall 31 of the connection 14, before referred to. The pipe may be operated by a handle 32, and preferably the pin is withdrawn from engagement with the wall 31 against the action of a coil 70 spring 33.

When the stop pin is released, the siphon pipe 20 may be revolved by means of the handle 8 and, when its suction end 24 contacts with the inner surface of the wall of the 75 drying cylinder, the operator can tell by the feel when this has occurred. After the end has been so positioned, it is adjusted to be moved the required distance away from the wall by connections which will now be described. As shown, the siphon pipe, at its outer end and near the bearing 22, passes through an adjusting ring or collar 34, which receives the threaded end 35 of an adjusting screw 36. It will be observed that 80 by manipulating the screw 36 up or down the siphon pipe is flexed and the suction end of the pipe is raised or lowered toward or from the inner surface of the drying cylinder.

It will be observed that the distance between the two supports 21, 22 of the siphon pipe is very much less than the distance the pipe extends beyond the inner end of the sleeve and into the dryer, so that a comparatively small flexing of the pipe at the adjusting collar or ring 34 produces a considerable movement at the suction end of the pipe. To facilitate this flexing movement, the suction pipe may be, as shown, 90 flattened at or closely adjacent the adjusting collar 34, as indicated at 37.

The adjusting screw may be supported in any suitable manner, but preferably will be so arranged that the number of turns given 105 the screw will be indicated so that the operator can tell how far he has moved the suction end of the siphon pipe. In the particular construction illustrated, the screw is provided with a thrust collar 38 in a recess, 110 indicated at 39 in Fig. 5, formed in a boss 40 on the connection 14, before referred to. Screwed into this boss is a plug 41, which has an inset portion 42 provided with a number of notches with which registers a spring 115 finger 43 carried on a nut 44 turning with the screw 36. A lock nut 45 and packing 46 may be provided for holding the parts in assembled position.

As before stated, the slight movement 120 given the pipe by the adjusting screw produces a sufficient movement in the cylinder, and this movement of the pipe in the inner end of the sleeve 12 may be provided for by slightly rounding the spider 21, as indicated at 47, see particularly Fig. 4, and this spider is also provided with passages 48 to permit the steam to pass from the chamber 15 through the sleeve and into the cylinder journal 3.

If desired, a collar 49 and packing 50 may be provided for effecting the steam joint between the chambers 15, 17, before referred to, this collar and packing surrounding the 5 siphon pipe and being held in steam-tight relation by the pressure of the steam in the chamber 15.

The operation of the device is believed clear from the foregoing, but may be briefly 10 recapitulated as follows: When it is desired to determine whether the siphon is in proper position, the operator by manipulating the adjusting screw 36 may bring the end of the siphon pipe into contact with the inner 15 surface of the dryer cylinder, and this he can readily determine by loosening and operating the handle 27. When he finds that the suction end of the pipe is in contact, he then turns the adjusting screw 36 a given distance 20 in the opposite direction and thus by the aid of the notched disc can tell the exact position of the end of the pipe relatively to the inner surface of the cylinder, it being understood, of course, that each notch represents a certain distance that the end of the 25 pipe is raised by the operation of the screw. It will be observed, furthermore, that these operations can all be done conveniently from the outside, thus greatly simplifying inspection and adjustment.

While the invention has been shown and described in its preferred form, it will be understood that various changes may be made in the specific construction employed 35 for supporting and operating the siphon tube and that the invention is, therefore, not to be limited to this specific construction, but that this can be changed as desired within the scope of the claims.

40 What I claim is:

1. In a dryer mechanism for paper making machines, the combination of a dryer roll, means for admitting steam thereto, a siphon pipe extending into the roll closely adjacent the inner surface thereof, and means exterior of the roll for flexing the siphon pipe to adjust its suction end with respect to the roll surface.

2. In a dryer mechanism for paper making machines, the combination of a dryer roll, means for admitting steam thereto, a siphon pipe extending into the roll closely adjacent the inner surface thereof, means for holding the pipe against rotation relatively to the roll, and means exterior of the roll for flexing the pipe to adjust its suction end to and from the roll surface.

3. In a dryer mechanism for paper making machines, the combination of a dryer roll, means for admitting steam thereto, a siphon pipe extending into the roll and shaped to closely approach the inner surface thereof, means for holding the pipe against rotation relatively to the roll, means for releasing the holding means so that the pipe

may be rotated, and two independently operable means for adjusting the suction end of the pipe with respect to the roll surface.

4. In a dryer mechanism for paper making machines, the combination of a dryer 70 roll, means for admitting steam thereto, a siphon pipe extending into the roll and shaped to closely approach the inner surface thereof, means for holding the pipe against rotation relatively to the roll, means for releasing the holding means so that the pipe may be rotated, and means for flexing the siphon pipe to adjust its suction end with respect to the roll surface.

5. In a dryer mechanism for paper making machines, the combination of a dryer roll, means for admitting steam thereto, a siphon pipe extending into the roll closely adjacent the inner surface thereof, a support for the pipe, a packing gland and a 80 bearing for the pipe support adjacent the gland but independent thereof, and means for adjusting the suction end of the siphon pipe with respect to the roll surface.

6. In a dryer mechanism for paper making machines, the combination of a dryer roll, means for admitting steam thereto, a siphon pipe extending into the roll closely adjacent the inner surface thereof, a sleeve enclosing the pipe, a packing gland about 90 the sleeve, a bearing adjacent the gland but independent thereof having rotary engagement with the sleeve, and means for flexing the siphon pipe to adjust its suction end with respect to the roll surface.

7. In a dryer mechanism for paper making machines, the combination of a dryer roll, means for admitting steam thereto, a siphon pipe extending into the roll closely adjacent the inner surface thereof, and an adjusting screw for flexing the siphon pipe to 105 adjust its suction end with respect to the roll surface.

8. In a dryer mechanism for paper making machines, the combination of a dryer 110 roll, means for admitting steam thereto, a siphon pipe extending into the roll closely adjacent the inner surface thereof, an adjusting screw for flexing the siphon pipe to adjust its suction end with respect to the roll surface, and means for indicating the adjusting movement of the screw.

9. In a dryer mechanism for paper making machines, the combination of a dryer roll, means for admitting steam thereto, a 120 siphon pipe extending into the roll closely adjacent the inner surface thereof, an adjusting screw for flexing the siphon pipe to adjust its suction end with respect to the roll surface, and a flattened portion in the pipe adjacent the adjusting screw.

10. In a dryer mechanism for paper making machines, the combination of a dryer roll, means for admitting steam thereto, a 130 siphon pipe extending into the roll closely

adjacent the inner surface thereof, means for flexing the siphon pipe to adjust its suction end with respect to the roll surface, and a flattened portion in the pipe adjacent to the flexing means.

11. In a dryer mechanism for paper making machines, the combination of a dryer roll, means for admitting steam thereto, a siphon pipe extending into the roll closely

10 adjacent the inner surface thereof, a handle for rotating the pipe relatively to the roll, means for locking the handle against rotation, and adjusting mechanism for moving the suction end of the pipe with respect to the roll surface.

12. In a dryer mechanism for paper making machines, the combination of a dryer roll, means for admitting steam thereto, a siphon pipe extending into the roll closely 20 adjacent the inner surface thereof, and two independent adjusting means operable while the machine is running for adjusting the suction end of the pipe with respect to the roll surface.

13. In a dryer mechanism for paper making machines, the combination of a dryer roll, means for admitting steam thereto, a siphon pipe extending into the roll closely adjacent the inner surface thereof, and 30 means operable while the machine is running for flexing the siphon pipe to adjust its suction end with respect to the roll surface.

14. In a dryer mechanism for paper making machines, the combination of a dryer roll, means for admitting steam thereto, a siphon pipe extending into the roll closely adjacent the inner surface thereof, a sleeve around the pipe, a rocking bearing for the pipe in one end of the sleeve, a fixed bearing 40 for the pipe, and adjusting mechanism between the bearings for adjusting the suction end of the pipe with respect to the roll surface.

15. In a dryer mechanism for paper mak-

ing machines, the combination of a dryer 45 roll, means for admitting steam thereto, a siphon pipe extending into the roll closely adjacent the inner surface thereof, a sleeve around the pipe, a rocking bearing for the pipe in one end of the sleeve, a fixed bearing 50 for the pipe, and flexing mechanism between the bearings for adjusting the suction end of the pipe with respect to the roll surface.

16. In a dryer mechanism for paper making machines, the combination of a dryer 55 roll, means for admitting steam thereto, a packing gland, a bearing separated from but having a common support with the gland, and a sleeve having rotary engagement with both the bearing and the gland.

17. In a dryer mechanism for paper making machines, the combination of a dryer roll, a hollow journal therefor, means for admitting steam thereto, a stationary sleeve, a packing gland, a bearing independent of 65 the gland, said gland and bearing having rotary engagement with the sleeve, and a common support for the gland and bearing.

18. In a dryer mechanism, the combination of a dryer roll, means for admitting steam to the roll, a siphon pipe extending into the roll closely adjacent the inner surface thereof, means for rotating the pipe to adjust its suction end with respect to the roll surface, and means for flexing the pipe 70 to effect a further adjustment of its suction end.

19. In a dryer mechanism, the combination of a dryer roll, means for admitting steam to the roll, a siphon pipe extending into the roll closely adjacent the inner surface thereof, and two independent means operable exteriorly of the roll for adjusting the end of the suction pipe relatively to 75 the roll surface.

In testimony whereof, I have hereunto set my hand.

CHARLES W. VALENTINE.
